CAM AND FOLLOWER MECHANISM

Jules Gressel and Paul Gressel, Guebwiller, France, assignors to Nouvelle Societe de Construction ci-devant N. Schlumberger & Cie., Guebwiller, France, a company

Application October 3, 1947, Serial No. 777,784
In France May 7, 1947

4 Claims. (Cl. 74—54)

1

The invention has for its object to provide improvements in the mechanism for controlling the movement of the nipper jaws in combing machines of the rectilinear type proceeding from the basic Heilmann's system, which are used for the combing of filamentous materials such as cotton, wool, tows, and the like.

It is known that the control of the lower jaw of the nipper, and in certain cases also that of the upper jaw, is generally effected by means of an articulated lever actuated by a roller which co-operates with a cam. The continuous contact between the roller and the cam is obtained by means of a spring which exerts either a pulling or a twisting action. Owing to the fact that the amplitude of the movements of the elements in question is fairly large, the spring is subjected to considerable stresses which are out of proportion to the object really required, viz, that of keeping the roller in contact with the cam, and which thus produce an excessive fatigue of the spring and also an excessive wear of the roller and of the cam.

In the device according to the invention, which eliminates the above-mentioned drawback, the roller controlling the movement of one of the jaws, or of both of the jaws, is held in contact with its cam by a spring which is fixed by one of its ends to an element secured to the roller, and by the other end to a movable fastening member which, by means of a positive drive, is given a movement which partly follows up, to a predetermined degree, the movement of the control roller or of the element secured to same, in such a manner that the work of the spring is reduced to a minimum.

According to another characteristic of the invention, the positive drive of the fastening member is obtained by means of a cam.

According to a further characteristic of the invention, the same cam simultaneously actuates the control roller and the fastening member.

According to a still further characteristic of the invention, the same spring is used to press the control roller and also the fastening member against their respective cam surfaces.

Other characteristics and advantages of the invention will moreover become apparent from the ensuing description taken with reference to the accompanying drawings, in which:

2

Fig. 1 is a diagrammatic view in side elevation of a controlling device according to the invention, provided with a draw-spring, the nipper being assumed to be in the open position;

Fig. 2 is a corresponding front view;

Fig. 3 is a similar view to Fig. 1, corresponding to the closed position of the nipper, and

Fig. 4 is a diagrammatic plan view of a modification provided with a torsion-spring.

In Figs. 1 to 3, which show a device for actuating the lower jaw provided with a draw-spring, 1 designates the upper jaw and 2 the lower jaw of the nipper, intended to co-operate with the circular comb 3.

15 The lower jaw 2 is secured to a lever 4 which can rock about a pivot 5 and which is pivotally connected at 6 to a rod 7. Said rod is secured, at its lower part, to a jaw 7^a which is pivotally connected at 7^b to a lever 8 which can rock about a pivot 9. The front end of the lever 8 supports a roller 10, the spindle 10^a of which engages a flat portion provided in a slide 10^b where its position can be adjusted by means of an adjusting screw 11. The roller 10 co-operates with a cam 12 which can rotate about pivot 13.

20 A lever 14, which can rock about a pivot 15, supports at its front end a roller 16 which also co-operates with the cam 12.

25 A draw-spring 17 is attached, on the one hand, to the lever 8, and on the other hand is secured to the lever 14 by means of a part 18 which enables the tension of the spring 17 to be adjusted and which bears against the lever 14.

30 The foregoing device operates as follows: If it is assumed that the nipper is open (Fig. 1), the roller 10 is in contact with the region B of the cam 12 where said cam is of smallest diameter so that the lower jaw 2 of the nipper is in its highest position in which it is remote from the circular comb 3. At the same time, by the action of any control device not shown, the upper jaw 1 is also located in its highest position, the relative positions of the two jaws 1 and 2 being such that the nipper formed thereby is open.

35 At this stage of the operation, the roller 16 bears against the portion D of the cam 12 where the diameter of same is largest so that the fastening member 18 of the spring 17 assumes its lowest position.

After inserting the sheet portion to be combed in the nipper, said nipper effects its closing movement and at the same time moves towards the circular comb 3. The movement of the lower jaw 2 is controlled by the rotation of the cam 12 in the direction of the arrow so as to bring first the region A and then the region D under the roller 10 and lift same. The lifting of the roller 10 causes the lever 4 to swing the jaw 2 towards the circular comb 3. At the same time, the upper jaw 1 has been moved downwards by the action of its control device so as to close the nipper on to the sheet.

The swinging movement of the lever 8 produced by the co-operation of the roller 10 with the cam 12 tensions the spring 17. However, this tension of the spring 17 is limited by the simultaneous swinging movement of the lever 14, since while the portion D of the cam 12 comes under the roller 10, the portion B comes opposite the roller 16 so that the lever 14, by the action of the spring 17, effects a swinging movement that has the effect of producing an upward movement of the fastening member 18 which partly follows up the upward movement of the upper fastening point of the spring 17 on the lever 8. In this manner, the spring 17 is protected from any excessive tension despite the large amplitude of the movement of the roller 10.

The closing position of the nipper is shown in Fig. 3. It can be seen therein that the roller 10 co-operates with the portion D of the cam 12, the portion B of which is at that instant located opposite the roller 16 so that the relative positions of the rocking levers 8 and 14 vary comparatively little. The nipper formed by the jaws 1 and 2 has closed and moved towards the circular comb 3.

Fig. 4 shows a plan view of a modification provided with a torsion-spring. In this modification, the lever 19 corresponding to the lever 8 of Figs. 1 to 3 is journalled on a pivot 22 by means of its hub 21. Said lever supports at the front end thereof a pivot 24 on which is journalled a roller 23 co-operating with a cam 25. Said cam is fixed on a rotary shaft 26 which supports a second cam 29 co-operating with a roller 28 which is journalled on a lever 27 which can rock about the pivot 22 by means of its hub 30.

The lever 19 actuates, by means of a connecting rod 20 corresponding to the rod 7 of the embodiment of Figs. 1 to 3, a device controlling the lower jaw of the nipper corresponding to the elements 4, 5, 6 of Figs. 1 to 3.

A helical spring 31 is wound round the pivot 22. The end 31^a of said spring is secured to the lever 19, whereas the other end 31^b is fixed to the hub 30 of the lever 27. The spring 31 bears the rollers 23 and 28 against their respective cams. The cams 25 and 29 are so arranged that, when the lever 19 effects a rocking movement about the pivot 22 by the action of the roller 23 co-operating with the cam 25, the lever 27 effects a rocking movement in the same direction owing to the co-operation of the roller 28 with the cam 29. In this manner, the twisting of the spring 31 produced by the movement of its end 31^a caused by the rocking of the lever 19 is partly compensated for by the movement of the end 31^b due to the rocking movement of the lever 27. Thus, the twisting of the spring can be limited to a value that precludes any excessive fatigue of said spring.

Of course, the embodiments hereinbefore described and illustrated in the drawings are only

given by way of examples and it is obvious that it is possible to modify in any suitable manner the shape, the nature, the arrangement and the mounting of their elements, and also to make use of equivalent means, without thereby exceeding the scope of the invention.

We claim:

1. In a combing machine of the rectilinear type, in combination, a shaft, cam means carried on said shaft, a movable nipper jaw, a first roller engaging said cam means, a second roller engaging said cam means at the side of said shaft which is substantially diametrically opposite from said first roller, a support, a pair of levers pivoted to said support, each of said levers having a respective one of said rollers secured thereto, linkage means connected with said nipper jaw and pivotally engaging one of said levers, and a spring connected at its respective ends to said two levers so as to force said two rollers against said cam means from substantially opposite sides, the sum of the radii of portions of said cam means simultaneously engageable by said two rollers being approximately constant.

2. In a combing machine of the rectilinear type, the combination of a shaft, a cam mounted on said shaft, a movable nipper jaw, a first lever operatively connected with said nipper jaw, and a first roller mounted on said lever and engaging said cam so as to control the movement of said nipper jaw, with a second lever substantially parallel to said first lever, a support, first pivot means swingably securing said first lever to said support, second pivot means swingably securing said second lever to said support, a second roller mounted on said second lever and engaging said cam at the side of said shaft which is substantially diametrically opposite from said first roller, and a tension spring connected to both of said levers so as to force said two rollers against said cam from substantially opposite sides, the sum of the radii of diametrically opposite portions of said cam being substantially constant.

3. In a combing machine of the rectilinear type, in combination, a shaft, cam means mounted on said shaft, a movable nipper jaw, a first lever linkage means connected with said nipper jaw and pivotally engaging said lever, a first roller mounted on said lever and engaging said cam means so as to control the movement of said nipper jaw, a second lever, a rod pivotally supporting said two levers for relative swinging movement of said levers, a second roller mounted on said second lever and engaging said cam means at the side of said shaft which is substantially diametrically opposite from said first roller, and a torsion spring helically wound around said rod and secured to said two levers so as to force said two rollers against said cam means from substantially opposite sides, the sum of the radii of portions of said cam means simultaneously engageable by said two rollers being approximately constant.

4. In a combing machine of the rectilinear type, in combination, a shaft, a cam mounted on said shaft, a movable nipper jaw, a support, a first and a second lever, first and second pivot means swingably securing said first and second levers, respectively, to said support, a first and a second roller respectively mounted on said first and second lever, said rollers engaging said cam at substantially diametrically opposite points, linkage means connected with said nipper jaw and pivotally engaging said first lever interme-

diate said first roller and said first pivot means, and a tension spring connected to both of said levers intermediate the respective rollers and pivot means thereof, thereby forcing said two rollers against said cam from substantially opposite sides, the sum of the radii of diametrically opposite portions of said cam being substantially constant, the spacing of said first and second pivot means of said support being substantially equal to that of said rollers when in engagement with said cam.
